EGG CARTON

Louis Schwartzberg, Chicago, Ill.

Application May 26, 1939, Serial No. 275,927

1 Claim. (Cl. 229—29)

My present invention relates to improvements in egg cartons.

The very considerable business of transporting eggs from producers and collectors to middlemen and retail distributors is effected through the use of a two compartment case or crate in which are placed layers of cells separated by transverse partitions known as flats. The tops and bottoms of each stack of cells and flats are further protected by additional transverse elements known as pads or cushions.

The dimensions and proportions of the above mentioned elements have become very definitely fixed and standardized by necessities and conveniences disclosed and developed through a considerable experience, and such dimensions and proportions have been further fixed by railroad and other shipping regulations.

The case or crate above referred to has a capacity of thirty dozen eggs which puts it in the classification of wholesale distribution as but relatively few consumers purchase eggs in thirty dozen lots. For the retail trade the middlemen and retail distributors have developed quite a number of different packages which are generally known as egg cartons, and the variety of egg cartons which, up to the present has proved preferable, comprises a paper container provided with two parallel rows of six cells each, adapted to contain a dozen eggs. There is quite a latitude in sizes in commercial eggs and a great number of different varieties of such cartons have been designed, but the sizes of eggs have now definitely established cartons of a width which, when filled with eggs and repacked in the cases or crates, primarily used for containing the cells and flats, leave something like an half inch of vacant space which requires the insertion of wedges or other dunnage to prevent the movement of the cartons within the cases or crates and the breakage of the contents of the cartons.

It will hereafter be seen that my primary object in the production of the invention herein disclosed, was to provide a design for a carton which, when packed in cases or crates, would not require the employment of additional packing elements or dunnage, and, which, at the same time, would retain substantially the same dimension of cell for the receipt of the eggs which has been determined by experience to be so convenient and necessary. I have discovered that the additional desired width of carton to secure the necessary snug fit in the cases or crates may be secured by widening the tops of

the cartons without disturbing the dimensions of the bottoms and that the transverse cross partitions, necessary in providing the six cells in each row, may be advantageously formed and obliquely disposed so as to give additional bracing between the side walls, support the egg suitably upon its end and facilitate both the insertion into and withdrawal of the eggs from the cells.

Almost all of the elements employed by me in my present design have been employed in slightly different forms in one or more of the many prior designs for egg cartons, but, so far as I know, not in the same form as I employ those elements and not with the same results. For instance, I myself, was one of the first to introduce what is known as double bottoms for such egg cartons but the divers ways hereafter shown in this application in which I provide double bottoms are believed to be specifically new and have, in each case, specific advantages. For further instance, it has heretofore been understood that it was advantageous to maintain the eggs in substantially a vertical position and in so doing V-shaped cells have been suggested but V-shaped cells, which engage what is known as the "belly" instead of the point of the egg, sacrifice the main strength of the egg shell, which is able to resist a much greater pressure when acting on the points of the eggs than would crush the egg when acting upon the sides or belly.

I have also had in mind in designing the herein disclosed structure, the provision of egg cartons which will continue to have the many desirable features of cartons now upon the market, such as strength, foldability, easy assembly and economy in material and manufacturing operations, as well as securing the main objects which are the production of a carton which may be snugly packed in an egg case or crate and the production of a carton which will permit the easier introduction into the cells during the filling operation and withdrawal of the eggs from the cells after the carton has been filled.

I have attained the aforementioned objects and results in the production of egg cartons by means of the structure illustrated in the accompanying drawings in which—

Fig. 1 is a blank or development which may be folded, as hereafter described, to provide one form of complete carton, with the exception of the central, longitudinal partition.

Fig. 2 is a blank of a suitable central, longitudinal partition for the cartons illustrated and described in this application.

Fig. 3 is a transverse section of a carton formed from such a blank as is shown in Fig. 1.

Figs. 4 and 5 are transverse diagrams illustrating two modified ways or manners in which double bottoms may be formed from integral blanks.

Figs. 6 and 7 are transverse diagrams illustrating additional modifications which may be employed in providing double bottoms from separate material, that is, the carton is blanked from one piece of material and the double bottom from another piece of material.

Fig. 8 is an horizontal section on section line 8-8 of Fig. 9 showing assembly of central, longitudinal partition with cells and

Fig. 9 is a vertical, longitudinal section on line 9-9 of Fig. 8 illustrating a like assembly to that shown in Fig. 8.

Similar reference characters refer to similar parts throughout the respective views.

As will be seen most clearly from an inspection of Figs. 1 and 3, the longitudinal strip 10 at the right end of the blank is glued to about the middle of the longitudinal strip designated by the reference character 20.

The longitudinal strips 11 and 17 form the upper wall of the false bottom when the longitudinal strips are folded and respectively designated by successive numbers as shown in Figs. 1 and 3. These strips 11 and 17 are slit in a desired manner, such as is shown at 11a and 17a, for the purpose of making the top or tops of the double bottom more springy and resilient for holding the eggs and preserving them from damage through jar or sudden movement.

The transverse cross partitions 19 are integral with the longitudinal strips 18 and 20 through the triangular connecting pieces 19a and the four sided opposite connecting pieces 19b. It will be seen, particularly from an inspection of Fig. 3, that the longitudinal strips 18 and 20, between which the transverse cross partitions 19 extend, are of substantially the same width but as the strip 18 extends upwardly from the top of the double bottom and the strip 20 extends downwardly to the bottom of the double bottom, the portions of the transverse cross partitions at the opening sides of the carton are materially lower than the portions of the transverse cross partitions which connect with the part of the carton from which the cover swings. By this slight change in structure of the transverse cross partitions 19, I am enabled to easily increase the width of the top for the purposes heretofore mentioned and give greater support to the eggs and at the same time make it actually easier to put the eggs in and to take them out of the cells. It will, of course, be realized that the insertion of the longitudinal partition 25 into the slots of and between the cross partitions 19 cause the cross partitions 19 to be swung from an horizontal position, as shown in Fig. 1, to a vertical position, as shown in Figs. 3, 8 and 9.

Each of the transverse cross partitions 19 are slotted downwardly from their upper edges, as at 19c, to accommodate the upper portion of the transverse longitudinal partition 25, shown separately in Fig. 2, and in assembly in Figs. 8 and 9.

The longitudinal transverse partition is for the further purpose of definitely positioning and furnishing greater rigidity to the transverse cross partitions 19. Between the portions of the longitudinal transverse partition which intersects with the transverse cross partitions 19, I have provided arcuate recesses 25a so as to disclose a

greater extent of contained eggs and render them more easily inserted and withdrawn. In Fig. 3 it will be seen that the lower edge portion of the longitudinal transverse partition extends below the lower edge of the transverse cross partitions 19 and below the top walls 11 and 17 of the double bottom. This lower extended portion at the recesses provided for the reception of the transverse cross partitions 19 is provided with hooks 25b to engage the lower edges of the transverse cross partitions 19.

As will be seen from an examination of Figs. 2 and 9, the shapes of the recesses in the longitudinal transverse partition 25, for the receipt of portions of the transverse cross partitions 19, are of different shapes with the hooks 25b extending in different directions. The shapes of the recesses I have found by experience to be most dependably effective and the direction of the hooks 25b is such that the hooks at the ends of the strip face toward the center and that the remainder of the hooks are in such a direction that after the depression of the transverse cross partitions 19, by insertion of the longitudinal transverse partition 25, a slight reverse movement of the inserted partition will cause an engagement of the hooks.

In Fig. 4, I have shown a central support for the top wall of the double bottom formed by gluing a T-shaped fold 21b in the bottom wall 21a, to the top wall 11a of the double bottom.

In Fig. 5 I have shown how a double bottom can be provided by making a longitudinal, outwardly facing channel 21c in the carton bottom 21d.

In Figs. 6 and 7 I have shown double bottoms quite similar to the double bottom shown in Fig. 3 except in Figs. 6 and 7 the double bottoms are formed of different pieces of material instead of being integral with the rest of the carton. In both Figs. 6 and 7 the double bottoms are glued in the cartons. In Fig. 6 no slot is provided for receiving the lower edge of the longitudinal transverse partition 25 and in Fig. 7 such a slot is provided.

Cartons made from quite a number of gauges of carton material in accordance with the illustrations and descriptions herein contained, will be found to be sturdy and dependable containers for eggs which will fit snugly, without extra dunnage or packing, in standard egg cases or crates. The wider top of such cartons sufficing to secure such snugness of fit while the greater extent and manner of disposal of transverse cross partitions, together with the size of bottom found desirable by experience, serves to hold and support the individual eggs upon their ends without exerting any pressure whatsoever upon their bellies. My present carton is so designed that automatic machinery capable of cutting and folding the blanks, which class of machinery is already well known, may be arranged for making the cartons automatically.

Having described my invention what I claim is new and desire to secure by Letters Patent is:

An egg carton, comprising a blank having transverse fold lines defining a plurality of longitudinal strips, said blank being foldable to form front and back walls of unequal height said walls being outwardly inclined with respect to the vertical and with respect to each other with the rear wall higher than the front wall, one of said longitudinal strips being wider than the bottom of said carton extending between and integral with both the higher top edge of the rear wall

and the lower top front edge of the front wall, said integral longitudinal strip being cut to provide a plurality of cross partitions having slots in their upper edges and a separate longitudinal transverse partition provided with apertures in its lower edge adapted to cooperate with said transverse cross partitions and the slots therein,

5 certain of said integral, longitudinal strips comprising a plural bottom, one of the layers comprising said plural bottom being centrally folded so as to constitute a central, longitudinal brace between said layers.

LOUIS SCHWARTZBERG.
